UNITED STATES PATENT OFFICE.

HENRY L. PEREZ, OF YONKERS, NEW YORK, AND THOMAS VEITCH, OF ENGLEWOOD, NEW JERSEY.

FOUNTAIN-PEN.

1,393,903.

Specification of Letters Patent.

Patented Oct. 18, 1921.

Application filed April 29, 1920. Serial No. 377,575.

To all whom it may concern:

Be it known that we, HENRY L. PEREZ and THOMAS VEITCH, citizens of the United States, and residents of Yonkers, in the county of Westchester and State of New York, and Englewood, in the county of Bergen and State of New Jersey, respectively, have invented certain new and useful Improvements in Fountain-Pens, of which

10 the following is a specification.

The present invention relates to fountain pens.

Ordinary fountain pens hold but a relatively small supply of ink, and their usefulness is conditioned upon access to an ink supply at frequent intervals. It has been proposed heretofore to use tablets or powder, capable, by the addition of water, of forming a writing fluid or ink, said tablets or powder, 15 as the case may be, being stored in a magazine, forming part of the fountain pen. In these constructions, the user, in order to place a tablet or a predetermined quantity of powder into the pen barrel, ordinarily 20 must detach the magazine, or a part thereof, from the pen, which is a rather inconvenient and annoying operation.

The main object of the present invention is to provide a fountain pen, having an ink-paste containing magazine, in combination with a simple and efficiently operating mechanism for forcing, at will, suitable quantities of ink-paste into the pen barrel, containing water for dissolving the paste and thereby 35 producing a writing fluid.

Another object of the invention is to so design the ink-paste magazine that it forms part of the barrel, thereby making it impossible to mislay the same, the paste charging means being, preferably, so arranged that it constitutes the means for closing the opening of the magazine, through which the filling operation takes place.

A further object of the invention is to so construct the communication between the pen barrel and the paste magazine that the fluid in the barrel is effectively prevented from entering the said magazine.

A still further object of the invention is to produce a fountain pen of the type described, which is capable of manufacture upon a commercial scale, or in other words one which is not so difficult to make as to be beyond the reasonable cost of such a contrivance.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

A few of the many possible embodiments of the invention are illustrated in the accompanying drawings, in which:—

Figure 1 is a longitudinal sectional view of a fountain pen constructed in accordance with the present invention; Figure 2 is a similar view of a portion of a modified construction; Fig. 3 is a section taken on line 3—3 of Fig. 2, on a larger scale; and Fig. 4 is a longitudinal section through a portion of a further modification of the invention.

Referring now first to Fig. 1 of the drawings, the numeral 10 indicates the barrel of a fountain pen, carrying at its lower end the pen-holder section 11 in the usual manner of fountain pen constructions. A transverse partition 12 is formed in the barrel in proximity of its upper end, said partition being provided with a small opening 13, controlled by a check valve, for instance a ball valve 14, which is held by means of a spring 15 upon its seat, said valve opening toward said pen-holder section, that is to say toward the fluid reservoir 16, disposed below said partition.

The barrel section above the partition is cylindrical and provided with interior screw threads 17, in mesh with those of a plug 18, the latter closing the last-mentioned barrel section, which constitutes a magazine for the ink material 19, that may be either a paste or viscous material. The outer end of the plug is provided with a milled knob 20, to facilitate the rotation thereof, while upon its inner end is mounted, in any suitable manner, a packing washer 21 of leather or other suitable material, which serves at the same time as a friction lock for the said plug.

The magazine may be filled with ink-paste, or similar material, by detaching the plug 18. The said magazine, when partly

filled, holds a supply sufficient for several months, the plug, when in operative position, shown in Fig. 1 of the drawings, bearing against the ink material throughout the 5 area of the barrel, and the check valve 14 closing a communication between the magazine and the fluid reservoir 16.

In use, the reservoir 16 is filled with water in the usual manner, after which the 10 plug 18 is given a turn, or part of a turn, to force the desired quantity of ink material into the said reservoir, in which it quickly dissolves, whereby the pen is ready for use. In turning the plug in the proper direction, 15 to force ink material into the fluid reservoir, the valve 14 is unseated against the action of its spring 15, the latter seating the valve as soon as the turning movement of the plug ceases.

20 The modification shown in Figs. 2 and 3 of the drawings differs from the one above described, in that a disk-valve 22 is employed instead of the ball valve 14. This valve constituting a check valve is made in 25 the form of a cup-shaped body, the flat head 23 of which bears against the underface of the partition 12, while its cylindrical portion 24 fits snugly the inner face of the barrel 10. The cup-shaped body is made of a 30 suitable non-corroding, resilient material, for a purpose which will presently appear. In the flat head 23 is formed a substantially U-shaped slot 25, partly encircling the opening in the partition 12, while the cylindrical portion 24 of the said body is serrated 35 to form resilient teeth 26, which bear against the inner face of the barrel, thereby holding the valve in position without the aid of special fastening means. The friction between 40 these teeth and the valve is sufficient to prevent a movement of the cup-shaped body, when the plug 18 is screwed down to force ink material into the fluid reservoir 16. When the said plug is turned for the 45 purpose mentioned, the ink-material unseats that portion of the flat head 23 of the cup-shaped body which is bounded by the slot 25, the resiliency of the said body causing the said portion to occupy its seat and thereby 50 close the opening 13, as soon as the turning movement of the plug 18 ceases.

The several constructions herein described 55 may be combined with self-filling fountain pens, one embodiment being shown in Fig. 4 of the drawings. In this case the partition 12' is detachable from the pen barrel 10, and to this partition is attached the fluid containing rubber sack 30. An ordinary valve-disk 31 is employed for closing the 60 opening 13 in the partition. This valve disk functions as a check valve. Otherwise the construction and operation of the elements are the same as of those described in connection with Figs. 1 to 4, inclusive, of the 65 drawings.

It is obvious that, while herein specific valve constructions have been described for controlling the communication between the fluid reservoirs and magazines of the pens, others may just as well be employed without 70 departing from the invention, which lies mainly in the provision of an ink material containing magazine, in combination with means whereby suitable quantities of the ink material are forcibly fed into the fluid 75 reservoir.

What we claim is:—

1. A fountain pen including a barrel, a partition dividing the said barrel into a liquid reservoir and an ink-paste containing 80 magazine, said partition being provided with a check valve controlled opening through which said reservoir and said magazine are adapted to communicate, and means for forcibly feeding ink-paste from said 85 magazine into said reservoir.

2. A fountain pen including a barrel, a partition dividing the said barrel into a liquid reservoir and an ink-paste containing magazine, said partition being provided with 90 a check valve-controlled opening through which said reservoir and said magazine are adapted to communicate, and means for forcibly feeding varying quantities of ink-paste from said magazine into said reservoir. 95

3. A fountain pen including a barrel, a partition dividing the said barrel into a liquid reservoir and an ink-paste containing magazine, said partition being provided with a 100 check valve-controlled opening through which said reservoir and said magazine are adapted to communicate, and means reaching into said magazine only for forcibly feeding ink-paste from said magazine into 105 said reservoir.

4. A fountain pen including a barrel, a partition dividing the said barrel into a liquid reservoir and an ink-paste containing magazine, said partition being provided with 110 a check valve-controlled opening through which said reservoir and said magazine are adapted to communicate, and means reaching into said magazine only for forcibly feeding varying quantities of ink-paste from 115 said magazine into said reservoir.

5. A fountain pen including a barrel, a partition dividing said barrel into a liquid reservoir and an ink-paste containing magazine, said partition being provided with a 120 check valve-controlled opening through which said reservoir and said magazine are adapted to communicate, and a plug closing said magazine and bearing against the ink-paste therein for forcibly feeding ink-paste 125 from said magazine into said reservoir.

6. A fountain pen including a barrel, a partition dividing said barrel into a liquid reservoir and an ink-paste containing magazine, said partition being provided with a 130

- check valve-controlled opening through which said reservoir and said magazine are adapted to communicate, and a screw plug closing said magazine and bearing against the ink-paste therein for forcibly feeding ink-paste from said magazine into said reservoir.
7. A fountain pen including a barrel, a partition dividing said barrel into a liquid reservoir and an ink-paste containing magazine, said partition being provided with a check valve-controlled opening through which said reservoir and said magazine are adapted to communicate, and a plug closing said magazine and bearing against the ink-paste therein for forcibly feeding varying quantities of ink-paste from said magazine into said reservoir.
8. A fountain pen including a barrel, a partition dividing said barrel into a liquid reservoir and an ink-paste containing magazine, said partition being provided with a check valve-controlled opening through which said reservoir and said magazine are
- adapted to communicate, and a screw plug closing said magazine and bearing against the ink-paste therein for forcibly feeding varying quantities of ink-paste from said magazine into said reservoir.
9. A fountain pen including a barrel, a partition dividing said barrel into a liquid reservoir and an ink-paste containing magazine open at its end opposite said partition, said partition being provided with a check valve-controlled opening through which said reservoir and said magazine are adapted to communicate, said magazine being provided with interior screw-threads, and a plug having threads meshing with those of said magazine closing the latter and bearing throughout the area of said magazine against the ink-paste therein for forcibly feeding ink-paste from said magazine into said reservoir.

Signed at New York, in the county of New York and State of New York, this 9th day of April, A. D. 1920.

HENRY L. PEREZ.
THOMAS VEITCH.
